MACHINE FOR FINISHING FLOORING

Irvin F. Dittmar, Williamsport, Pa., assignor to
The Cromar Co., Williamsport, Pa., a corpora-
tion of Pennsylvania

Application April 2, 1930. Serial No. 441,110

19 Claims. (Cl. 91—39)

This invention relates to certain new and useful improvements in machines for finishing flooring and more particularly to means for applying a coating to the face of the strip in its passage through the machine, the object being to provide a novel form of brush for applying a coating to the strip in its passage therethrough.

Another object of my invention is to provide a brush which can be moved towards and away from the moving strip in order to regulate the thickness of the coating applied.

Another object of my invention is to provide a novel form of brush and mounting wherein the applying device can be moved forwardly or backwardly, tilted or turned, raised or lowered, in order to allow it to be readily adjusted into various positions in respect to the moving strip of flooring, the same being so mounted on its support that it can be readily removed therefrom.

Another object of the invention is to provide novel means for supplying a coating to a nozzle which is disposed within the brush so that the brush will be supplied constantly with the liquid to be applied to the strip, means being provided for regulating the supply.

A still further object of the invention is to provide a machine in which a strip of lumber, such as a strip of flooring, is adapted to be moved continuously through a guideway past the applying device by feed rollers so disposed in the machine that they feed the strip of flooring a certain distance and the following strip continues the feeding of the strip whereby a strip is always in position opposite the brush so as to prevent the liquid of the fountain brush from being discharged in case a strip should be moved out of transverse alignment therewith.

Another object of my invention is to provide a nozzle which is revolvably mounted and forms a liquid feed so as to discharge the liquid into the brush adjacent the ends of the bristles.

Other and further objects and advantages of the invention will be hereinafter set forth in the appended claims.

In the drawings,

Figure 1 is a side elevation of a machine constructed in accordance with my invention showing the applying device in position to coat one face of the strip in its passage therethrough;

Figure 2 is a vertical section showing by dashed lines the applying device tilted downwardly in order to allow the brush to be inspected;

Figure 3 is a section taken on line 3—3 of Figure 2;

Figure 4 is an enlarged section taken on line 4—4 of Figure 1; and

Figure 5 is a detail longitudinal vertical section showing the brush advanced within the housing.

In the embodiment of my invention as herein shown, I illustrate a machine constructed substantially as shown in my application filed December 7, 1928, Serial Number 324,347, in which 1 indicates a frame having arranged thereon a guideway formed of upper and lower guides 2 and 3 between which a strip of flooring 4 is adapted to be fed by feed rollers 5, guiding rollers 6 being disposed at the feed end of the machine for guiding the strip in position to be forced into the guideway, whereby it will be engaged by the feed rollers and caused to move longitudinally through the guideway.

While I have shown certain details of construction of the machine, I am, of course, aware that my applying device is capable of being used with other constructions so long as a strip of flooring is fed continuously through a machine on edge and therefore I do not wish to limit myself to any details of construction of feeding and guiding means as I am aware that various changes can be made without departing from the spirit of my invention.

Mounted on the main frame 1 is an auxiliary frame 7 which is provided with an aperture through which extends a threaded end 8 of a supporting rod 9 which carries a collar 10 locked in position by a set screw 11, said rod being adapted to be clamped in the frame 7 by a nut 12 as clearly shown in Figure 1, whereby the supporting rod is mounted in a horizontal position.

In use I preferably employ a frame 7 which extends across the main frame 1 in order to allow the supporting rod 9 to be secured in either end thereof, whereby the applying device as herein-after fully described can be positioned to each side of the guideway in order to allow a coating to be applied to either face of the strip in its passage therethrough and in some instances the applying device is arranged to each side of the guideway whereby both faces of the strip will be coated in its passage therethrough.

The end of the rod 9 is provided with an annular groove 13 having a socket 14 and revolvably mounted on the rod 9 is a supporting block 15 which carries a screw 16 mounted in a threaded bore and provided with an end 17 which is adapted to extend into the socket 14 of the rod 9 so as to normally hold the block 15 in a horizontal position. By operating the screw 16 the end 17

can be withdrawn from the socket 14 so as to allow the block to be rocked or swung downwardly into a vertical position and by tightening up the bolt it will engage the end of the annular groove so as to hold the block into vertical position.

My improved construction of applying device which is carried by the block comprises a cylindrical head 18 which has secured to one end thereof a brush housing 19 substantially rectangular in form which is adapted to be arranged to one side of the strip, the vertical edges of the housing being cut away as shown at 20 and rounded.

15 Mounted within the rectangular housing 19 is a box-shaped brush back 21 carrying bristles 22 forming a brush which is adapted to contact with the face of the strip as the strip moves past the same in order to apply a coating to the face of the strip as will be later described. Secured within the box-like back 21 of the brush is an internally threaded nipple 23 through which extends an externally threaded nozzle 24 which is revolubly mounted in the head and carries a detachable plug 25 at its end, the orifice of which controls the discharge of liquid and this plug is threaded within the end of the nozzle and in use when coating with a certain material I use a plug with a certain size orifice and with a coating of other materials I use a plug with a different size orifice, so that I am able to control at the point of discharge the liquid being fed to the brush.

20 The nozzle 24 terminates at its opposite end in a tubular extension 26 having an annular collar 27, the longitudinal movement of which is limited by a shoulder 28 at one end and by a packing ring 29 at its other end, said packing ring being externally threaded and screwed into and internally threaded socket 30 by a spanner wrench or the like and locked into its adjusted position by a set screw 31, said ring having an oblique face adapted to be engaged by a packing 32 which is engaged by an externally threaded ring 33 threaded into the socket 30 so as to form a stuffing box for the tubular extension of the nozzle whereby as the nozzle is rotated, any leakage of liquid is prevented.

25 The tubular extension carries a hand wheel 34 for rotating the same and the end of the extension is internally threaded as shown at 35 in which a plug 36 is secured so that when the plug is removed a wire can be passed longitudinally through the extension and nozzle in order to remove any obstruction within the nozzle.

30 From the construction thus far described, it will be seen that I have provided a revoluble tubular nozzle which has a threaded portion extending through a ferrule fixed within the brush back whereby the brush can be moved towards and away from the strip so that as the brush wears, it can be advanced until practically the entire length of bristles have been used.

35 The brush is provided with reinforcing members A to each side of the ferrule as clearly shown and described in my companion application covering the brush and method of making the same for stiffening the bristles to form a dam to each side of the nozzle for holding the coating material fed by the nozzle in the brush whereby I am able 40 to use a smaller size brush and still obtain the desired result.

45 The tubular extension 26 of the nozzle 24 is provided with inlet ports 37 and 38 adapted to register with internally threaded inlets 39 and 40 formed in the head in which is adapted to be

50 screwed a threaded nipple 41 of a valve 50 which is provided with a threaded nipple 51 connected to a coupling 52, which in turn is connected to the outlet pipe 53 of a liquid container 54 in which the liquid to be applied to the strip in its passage through the machine is placed and from which it flows by gravity to the nozzle so as to produce a fountain brush, the supply of which can be controlled by the size of the orifice of the plug 25 and also by the valve 50. In the construction shown, the inlet 39 is closed by a plug 42 which provides means for connecting the fountain brush directly to a force feed supply as by removing the nipple 41 and substituting a plug 42 therefor, a threaded nipple of a feed pipe 50 can be inserted within the inlet 39 and liquid coating material could be forced under pressure directly to the nozzle.

55 In order to mount the head so that it can be moved towards and away from the strip in its passage through the guideway, I provide a tubular support 44 which is provided with a stem 55 mounted in an opening 56 formed in the block 15, said block being split as shown at 57 and having a bolt 58 extending across the slot so as to clamp the stem 55 in adjusted position within the block, which allows the tubular support to be swung at an angle in respect to the guideway or the face of the strip in its passage therethrough.

60 The tubular stem is formed hollow and provided with a threaded portion 59 in which works a threaded portion of a bolt 60 which is adapted to engage a cylindrical head 18 so as to clamp the head in its adjusted position and it will be seen that by this construction the head is free to move longitudinally within the tubular support and be locked in its adjusted position and in connection with the other adjustable features, the head can be adjusted into various angular positions, can 65 be tilted, swung upwardly or swung into a horizontal plane so as to swing it out of the path of travel of the strip in its passage therethrough.

65 In the construction herein shown I have provided means for detaching the liquid container from the head and so mounting the head within the cylindrical support that by loosening the bolt 60 the head can be detached from the cylindrical support whereby the brush and head can be removed and placed into any solvent so as to 70 thoroughly clean the same.

75 While I have shown a gravity feed for the brush, I am, of course, aware that a force feed could be used and that various changes in the details of construction herein shown can be made without departing from the spirit of my invention.

80 By constructing a brush with a nozzle disposed therein having means surrounding the bristles to each side of the nozzle so as to stiffen the bristles, and I provide a dam for the coating material being fed by the nozzle, I am able to manufacture a brush of smaller size and yet obtain the same result as the bristles are supported within the housing in such a manner that the coating 85 material is spread evenly on the strip of material in its passage therethrough.

85 In the operation of a machine constructed in accordance with my invention the liquid to be applied to the face of the strip is placed in the 90 liquid receiving container 54, it, of course, being understood that the valve 50 is in closed position. A strip of flooring is then placed between the guide rollers 6 and the operator forces it into the guideway formed by the guides 2 and 3 until 95

it is engaged by the feed rollers 5 and the strip is then forced through the guideway past the brush. The valve 50 is then opened and as the operator continues to feed strips through the machine, 5 one strip forces the other therethrough and in the passage of these strips through the machine a coating is applied to the face thereof, it, of course, being understood that after one strip has been moved so as to be opposite the brush the 10 valve 50 is opened and the brush is adjusted so as to apply the proper thickness of coating to the strip in its passage therethrough.

By having the head carrying the brush housing adjustable, the housing and head can be adjusted towards and away from the strip and by having the nozzle revolvably mounted and operated by a hand wheel, the operator after the initial setting of the housing can adjust the brush itself in respect to the face of the strip by operating 15 the hand wheel and as the hand wheel is rotated, the box-shaped brush back with its internally threaded ferrule is caused to reciprocate within the housing. This provides not only the means for adjusting the brush to apply the proper coating to the strip, but also provides a brush in which 20 means is provided for adjusting the same as the bristles wear whereby the full length of the bristles can be used and by having the brush mounted in a brush housing, I am able to use bristles 25 of a shorter length whereby the flexing of the same is decreased whereby the life of the brush is greatly increased.

By employing supporting rods of different 30 lengths, I am able to position the brush at the proper place on the machine to apply a coating and by having the supporting sleeve revolvably mounted in the brush and revolvably mounted in the block, I am able to swing the brush in a horizontal position so as to properly align the brush 35 in respect to the surface of the strip. In mounting the block on the supporting rod 9 so as to allow it to oscillate, the brush can be moved vertically in order to swing it into such position that it can be readily inspected by the operator.

From the foregoing description it will be seen 40 that I have provided a machine for coating strips of lumber having a fountain brush so mounted that it can be adjusted in respect to the face of the strip so as to apply the proper thickness of coating to the strip in its passage therethrough and while I have illustrated the nozzle and brush being disposed within the upper portion thereof so that the supply will be in the upper portion 45 of the brush, I am aware that the nozzle can be disposed in any suitable position without departing from the spirit of my invention and this application is a companion application of an application executed even date herewith in which I have disclosed a machine for coating strips of 50 lumber having novel means for feeding the coating material to the fountain brush.

What I claim is:

1. In a machine for coating strips of lumber, the combination with means for guiding and moving the strip therethrough, of a brush housing 55 adjustably mounted to be moved in different directions in respect to said guiding means, a brush movably mounted within said housing having its bristles extending outwardly beyond the edges thereof, means for adjusting said brush in said housing, and means for supplying liquid to the interior of said brush.

2. In a machine for coating strips of lumber, the combination with means for guiding and moving the strip of lumber therethrough, of a

brush housing adjustably mounted in respect to said guiding means, a brush provided with a threaded member, a threaded revoluble nozzle mounted in said threaded member, and means for rotating said nozzle to adjust said brush in respect to said guiding means. 80

3. In a machine for coating strips of lumber, the combination with means for guiding and moving a strip of lumber therethrough, of a support arranged to one side of said guiding means, a brush adjustably mounted on said support, and means for adjusting said brush longitudinally, vertically and laterally in respect to said guiding means. 85

4. In a machine for coating strips of lumber, the combination with means for guiding and moving a strip of lumber, of a support arranged to one side of said guiding means, a fountain brush adjustably mounted on said support in respect to said guiding means for applying a coating to the face of the strip in its passage therethrough, said brush being mounted to move longitudinally, vertically and laterally in respect to said guiding means and means for locking said brush in adjusted position. 90

5. In a machine for coating strips of lumber, the combination with means for guiding and moving a strip of lumber therethrough, of a fountain brush mounted to one side of said guiding means, said brush having a nozzle embedded 95 therein, and means for rotating said nozzle to adjust said brush in respect to said guiding means. 105

6. In a machine of the kind described, a fountain brush comprising a head carrying a brush 110 housing, means for adjusting said head, a nozzle revolvably mounted in said head and means for rotating said nozzle to move said brush within said housing and means for supplying liquid to said nozzle. 115

7. A fountain brush for coating machines comprising a brush housing having an adjustably mounted head, a brush mounted in said housing, a nozzle revolvably mounted in said head and extended into said brush and means for connecting said nozzle to said brush for causing said brush to move in said housing upon the rotation of said nozzle. 120

8. In a machine for coating strips of lumber, a fountain brush disposed to apply a coating to 125 the face of the strip in its passage therethrough, said brush comprising an adjustably mounted head having a revoluble nozzle mounted therein, a brush surrounding said nozzle, means for connecting said brush to said nozzle to cause said 130 brush to move in said housing upon the rotation of said nozzle and means for supplying a coating material to said nozzle.

9. In a machine for coating strips of lumber, the combination with means for guiding and propelling a strip therethrough, of a fountain brush for applying a coating to the face of the strip in its passage therethrough, said brush having a nozzle embedded therein provided with a detachable plug, means for supplying coating material 135 to said nozzle and means for regulating the supply of the material to said nozzle. 140

10. In a machine for coating strips of lumber, the combination with means for guiding and propelling a strip of lumber therethrough, of means 145 for coating a strip of lumber in its passage therethrough comprising a brush housing adjustably mounted in respect to said guiding means, a brush slidably mounted within said housing having an internally threaded ferrule, an externally 150

threaded nozzle working through said ferrule and terminating adjacent the free end of said brush, said nozzle being provided with inlet ports and a liquid container having a valve for controlling the passage of liquid therethrough in communication with said inlet ports for regulating the supply of liquid to said nozzle.

11. In a machine for coating strips of lumber, the combination with means for propelling and 10 guiding a strip of lumber in its passage therethrough, of means arranged to apply a coating to the strip in its passage therethrough, said means comprising a brush housing with a brush adjustably mounted therein and means for adjusting 15 said brush within said housing for regulating the thickness of coating applied to said strip in its passage therethrough.

12. In a machine for coating strips of lumber, the combination with means for propelling and 20 guiding a strip of lumber in its passage therethrough, of a fountain brush disposed to one side of said guiding means for applying a coating to the face of the strip in its passage therethrough, said brush having a nozzle embedded therein 25 provided with a detachable plug having a restricted orifice for regulating the supply of coating material to said brush.

13. In a machine for coating strips of lumber, the combination with means for guiding and propelling a strip of lumber in its passage therethrough, of a supporting rod, a block adjustably mounted on said supporting rod, a stem revolvably mounted in said block having a supporting collar, a head carrying a housing adjustably mounted in 30 said collar, and a brush carried by said housing for applying a coating of liquid to the face of the strip in its passage therethrough.

14. In a machine for coating strips of lumber, the combination with means for guiding and 40 propelling a strip of lumber in its passage therethrough, of a horizontally disposed support, a block mounted to oscillate upon said support, means for locking said block in adjusted position upon said support, a stem revolvably mounted in 45

50

55

60

65

70

75

said block, means for locking said stem in adjusted position within said block, a supporting collar carried by said stem, a head adjustably mounted in said supporting collar, means for locking said head in adjusted position within said collar, a brush housing carried by said head and a fountain brush adjustably mounted within said housing.

15. A fountain brush for coating machines having a nozzle adjustably mounted in the bristles thereof and provided with means for reinforcing the bristles beyond the end of the nozzle to form a dam around said nozzle.

16. In a machine for coating strips of lumber, the combination with means for guiding and moving a strip of lumber therethrough, a nozzle adjustably mounted to move in three different directions to one side of said guiding means and a brush adjustably mounted on said nozzle.

17. In a machine for coating strips of lumber, the combination with means for guiding and moving a strip of lumber therethrough, a housing arranged to one side of said guiding means having a nozzle disposed therein means for adjusting said housing in respect to said guiding means 100 and a brush adjustably mounted on said nozzle within said housing.

18. In a machine for coating strips of lumber, the combination with means for guiding and moving a strip of lumber therethrough, of a nozzle 105 adjustably mounted to be moved in different directions in respect to said guiding means and a brush adjustably mounted on said nozzle.

19. In a machine for coating strips of lumber, the combination with means for guiding and 110 moving a strip of lumber therethrough, a support arranged to one side of said guiding means, a housing adjustably mounted on said support, means for adjusting said housing in respect to said guiding means, a nozzle disposed in said 115 housing and a brush adjustably mounted in said housing surrounding said nozzle.
